UNITED STATES PATENT OFFICE.

WILLIAM B. BOLLES, OF MILWAUKEE, WISCONSIN.

ANTIPANIC-LOCK-OPERATING MECHANISM.

Application filed July 1, 1922. Serial No. 572,178.

This invention relates to anti-panic lock operating mechanisms and more particularly either to lock operating devices adapted to be applied to the several ordinary types of door locks and latches, or to door bolts which by nature are made to provide ready exit at all times.

The present invention is an improvement over the devices disclosed in Patent No. 10 1,288,816, granted to me December 24, 1918, and Patent No. 1,383,974, granted to me July 5, 1921.

The main object of this invention is to provide a lock operating mechanism which 15 will operate satisfactorily without excessive wear upon the parts or danger of breakage should the mechanism be inaccurately positioned with reference to the lock in attaching to the door. The lock operating mechanism 20 constructed in accordance with the patents above referred to operates satisfactorily if properly applied to the door. However, it sometimes happens that through inexperience or otherwise the requirements for proper 25 installation are not satisfied. If the lock operating mechanism is not properly positioned, the lock operating projection may in its motion, experience an interference to its full motion after retracting the latch bolt its 30 full amount. Abuse will occur if the lock operating projection strikes hard against the lock operating member before the hand-grip strikes its abutments; the impact being taken by the lock operating projection instead of 35 by the abutments as intended.

Only a slight change in the position of the lock operating mechanism would put the lock operating mechanism in proper position. The new screw holes, however, would be so 40 close to the old ones that the mechanism would be insecure. It is therefore not feasible to change the position of the lock mechanism to correct a slight inaccuracy in the original mounting. When it happens that a 45 lock operating mechanism is slightly misplaced in attaching to the door, violent actuations of the trip lever would tend to weaken the lock operating projection and might eventually cause the projection to break off 50 or break other parts either actuating or actuated by the lock operating projection, and render the mechanism inoperative.

The present invention overcomes this difficulty by providing a lock actuating mechanism in which the member carrying the lock operating projection is so cushioned

that excessive pressure cannot be exerted upon the projection should it strike the lock member hard and the actuating lever will continue to move until it strikes its abutment. 60 Other objects will be apparent from the following description in connection with the accompanying drawings.

Referring to the accompanying drawings forming a part of this specification, Fig. 65 1 is an elevation of a door with the lock actuating mechanism applied thereto. Fig. 2 is a side elevation of the lock casing detached. Fig. 3 shows partially in elevation and partially in section a door equipped 70 with a lock and lock operating mechanism. Fig. 4 shows a section through the casing. Fig. 5 is a perspective view of the slide block. Fig. 6 shows a rear elevation of the lock actuating mechanism showing the invention applied to a double acting lock actuator. Fig. 7 is a view of the lock actuator shown in Fig. 6 partially in side elevation and partially in section. Fig. 8 shows a rear elevation of a modified form of double acting 75 lock actuator. Fig. 9 is a rear elevation of a door bolt actuator. Fig. 10 is a sectional view showing another form of door bolt actuator.

Referring to the accompanying drawings, 80 Fig. 1 shows a door 1 which is hinged and mounted between the usual door jambs 2. In the edge of the door there is mortised a lock such as shown in Fig. 2. This lock is of a well known type which may be purchased 85 on the open market, and no particular description of the lock will be given except to indicate the portion of the lock which co-operates with the lock operating mechanism of my invention, and again at this point I 90 wish to state that in making reference to this particular lock, I do not confine myself to a lock having the operating mechanism herein shown and described, as other locks and latches may be used which will co-operate with the lock operating mechanism in the manner herein described. It is to be 95 understood that the word "lock" as herein-after used in the specification and claims, in meaning, includes latch or bolt.

Referring to Fig. 2, the locking bolt or latch is indicated at 3. This latch has a rearwardly extending portion 4 which has a head 5. The head is engaged by the reciprocating member 6 which has a hooked 100 head 7 that engages with the head 5. At the rear portion the member 6 engages with

an arm 8 of the pivoted lever, this lever being pivoted at 9. The lever also has an arm 10 which cooperates with an operating member 11. The operation of so much of the lock as shown and described will be readily understood, for when the lever is pressed upwardly the arms 10 and 8 are moved in a direction which results in pulling the latch or bolt 3 inwardly with respect to the lock casing. The various elements of the lock are so arranged that by spring pressure they will be returned to their normal position when pressure against the member 11 is released.

Upon the inside of the door 1 there is secured a casing 12. The casing 12 is formed to provide a vertical guideway 13 in which is mounted a slide bar 14. The slide bar 14 has a sliding fit with the walls forming the casing space. A portion of the casing space is designated 16 at the upper end of the guideway 13. A suitable spring connection which may comprise a single spring or a plurality of springs is provided between the slide bar 14 and casing. As shown, a coil spring 17 is placed in the casing space 16 and bears against the upper end of the slide bar 14 whereby it serves to normally hold the slide bar 14 in its lowermost position. The casing has a back plate 18 secured thereto and in contact with the door. The casing has pivot receiving bosses 19 projecting from its outer face. The bosses 19 receive the pivot 20 of an actuating lever 21, by means of which the mechanism is operated. A cross bar 22 is fixed to the outer end of the actuating lever 21. An arm 23 corresponding to the lever 21 only of the opposite hand is secured to the opposite end of the cross bar 22 and is pivoted at its inner end to pivot bosses 24 similar to the bosses 19, extending outwardly from a plate 25 which is secured to the hinged side of the door. The levers by interchanging, are adapted to operate doors of either hand. The actuating lever 21 and the arm 23 at the opposite end of the cross bar each have a surface 27 below the pivot 20 which abuts against the face of the casing 12 when the operating lever is swung downwardly. In their uppermost position the operating levers engage the guard face of the casing wall integral with the outer edges of the triangular pivot bosses 19 and 24. The triangular bosses 19 and 24 extend below the pivot 20 to form a guard which prevents fingers being pinched between the surface 27 of the lever or arm and the casing when the lever is swung down. The actuating lever 21 has a head 28 which projects through an opening in the casing 12 and into a slot in the slide bar 14. The slide bar 14 has a slot extending lengthwise thereof which has a narrow lower portion 29 which receives the head 28 of the actuating lever, a central por-

tion 30 and an upper portion 31. The size of the several cross-sections of the slot may be relatively variable to meet operating conditions. A slide block 32 is mounted in the widened central portion 30 of the slot in the slide bar 14. The slide block 32 may but does not necessarily carry an upwardly projecting pin 33 which fits within a coil spring 34. The coil spring 34 bears upon the top of the block 32 and its upper end is seated against the top end of the slot part 31 in the slide bar 14. The back-plate 18 of the casing has a slot 35 adjacent its lower end which communicates with a recess 36 in the door 1 beneath the member 11 of the door lock. The slide bar 14 has a stud 37 projecting into the recess 36 and engageable with the operating member 11 of the door lock when the slide bar 14 is moved upwardly. The operating lever in its normal position extends downwardly from the pivot 20 so that the bar 22 is below the longitudinal axis of the pivot 20 carried by the triangular bosses 19. When the lever 21 is swung downwardly, the head 28 thereof engages the slide block 32, forcing the slide block upwardly against the spring 34 and forcing the slide bar 14 upwardly against the spring 17. As the slide bar 14 is raised, the stud 37 engages the lock operating member 11 to release the door latch. If the stud 37 reaches its limit of movement before the surface 27 of the actuating lever strikes against the casing 12, the slide block 32 will move upwardly against the action of the spring 34 until the abutment 27 of the actuating lever engages the casing 12.

The lock actuating mechanism just described may be applied in reverse position upon the door so that the operating bar moves toward the door above the pivot or the operating bar may be arranged vertically on the door and the projection on the slide may be arranged to co-act with the latch mechanism at the upper edge of the lock casing or at the rear edge thereof. Where it is desirable to prevent access from the outside of the building the usual door knob will be omitted and the latch will be operated solely by the operating mechanism on the inside. The antipanic lock operating mechanism is entirely independent of the latch operating cylinder and latch operating knobs may be provided upon either or both sides of the door as desired.

To provide means for retaining the door latch in retracted position at all times when desired, bosses 19 and the actuating lever 21 are provided with holes 38 and 38^a, which register when the operating lever is in its lowermost position and are adapted to receive a pin or the like.

It is in some instances preferable to have a lock operating mechanism in which the actuating lever is normally held in an inter-

mediate position and in which the door lock is released upon movement of the actuating lever in either direction. In Figs. 6 and 7 I have shown such a double acting actuator 5 adapted to be applied to an ordinary form of door lock, latch or bolt such as above described.

In this form of the invention a casing 39 has a slide bar 40 mounted for vertical movement therein. The slide bar 40 may be but need not necessarily be rectangular in cross section and may have a guide pin 41 fitting in a recess 42 at the upper end of the casing. A coil spring 43 is seated in the recess 42 and bears against the upper end of the guide pin 41. In some instances it may be preferable to have the coil spring approximately equal in outside diameter the dimension of the slide bar 40, in which case 15 the spring is kept in alignment by the back plate the front face wall of the casing and lateral interior casing walls which serve also to hold the upper end of the slide member 40 in proper alignment as it functions. The 20 spring is always under initial compression as its upper end bears against the closed upper end of the casing and the lower end of the spring engages the top end of the slide member 40. The spring 43 exerts 25 downward pressure upon the slide bar 40 and serves to return the slide bar to normal position after each actuation thereof. The lock operating mechanism shown in Figs. 6 and 7 is actuated by a lever such as above described. The slide bar 40 may have a slide slot similar to that of the slide bar 14 above described, in which there is a narrow lower portion for receiving the head 45 of the actuating lever, and an enlarged 30 central portion 46, and an upper portion 47. A slide block 48 fits in the enlarged central portion 46 of the slot and may but need not necessarily have a projecting horn 49 at its upper end upon which a coil spring 50 is 35 positioned. The coil spring 50 is seated in the narrow upper portion 47 of the slot and bears against the top of the block 48 to normally hold the block 48 against the shoulders at the lower end of the central portion 46 of the slot. The slide block 48 normally 40 holds the actuating lever in an intermediate position. When the actuating lever is depressed, the slide bar 40 is actuated in exactly the same way as the slide bar 14 above 45 described and actuates the lock releasing member through the stud 51 which is similar to stud 37 on the slide 14. For actuating the slide bar 40 when the actuating lever is lifted, the casing 39 has a centrally disposed horn 52 upon which a lever 53 is centrally pivoted. One end of the lever 53 carries a depending pivoted arm 54 which 50 may carry a bearing part such as a roller 55 at its lower end engaging the wall of the casing 39. The arm 54 has an inwardly pro-

jecting foot 56 which enters a recess 57 in the slide 40. The upper end of the recess 57 is at the lower end of the narrow portion 44 of the slot of the slide bar so that when the foot 56 is at the upper end of the recess 57, the head 45 of the actuating lever engages at its under side with the foot 56 and at its upper side with the slide block 48. A pivoted arm 58 is hung upon the opposite end of the lever 53. The arm 58 has a recess 59 which receives a laterally projecting stud 60 carried by the slide bar 40. The arm 58 has an end lug 61 which is formed to provide a seat for the coil spring 62. The stud 60 may but need not necessarily have a downwardly extending centering projection 63 which engages within the upper end of the coil spring 62. The recess 59 is of sufficient length to permit the necessary movement of the stud 60 therein. The arm 58 has a laterally projecting lug 65 below its connection to lever 53. The lug 65 projects into a notch 66 in the slide bar 40. The lug 65 is normally held in engagement with the shoulder at the bottom of the notch 66 by coil spring 62. The coiled spring 62 reacts between the projection 60 on the slide and the lower end of the link 58 tending to force the link downwardly and the slide upwardly. This relative movement of the link and slide is, however, prevented by the engagement of the projection 65 of the link 58 against the bottom of the notch 66 in the slide into which the projection 65 extends. Thus the spring 62 is rendered ineffective to produce any relative movement between the link and slide. However when the head 45 of the lever is moved down against the projecting foot 56 of the link 54 the link 54 is moved downwardly swinging the lever 53 about its pivot and raising the link 58. Upward pressure is then exerted upon the slide 40 through the compression spring 62, the compression spring 62 being stronger than the return spring 43 the slide will normally move upwardly with the link 58. However if the slide meets excessive resistance to movement due to the operating lug 51 being impeded in its movement the spring 62 can yield and prevent injury either to the lock actuating mechanism or to the mechanism of the lock. When the operating lever is swung upwardly, the head 45 thereof is swung downwardly against the inwardly projecting foot 56 of the arm 54, forcing the arm 54 downwardly, causing the lever 53 to swing about its pivot and raise the arm 58. Upward movement of the arm 58 exerts upward pressure upon the slide bar 40 through the coil spring 62 and moves the slide bar 40 upwardly against the action of spring 43, carrying the stud 51 into engagement with the lock operating member 11. If the stud 51 engages an overwhelming resistance be-

fore the actuating lever strikes its upper abutment, the coil spring 62 will permit continued movement of the actuating lever until it strikes its abutment, and prevents excessive impacts being exerted upon either the lock or lock operating mechanisms by the lock releasing stud.

In the modification shown in Fig. 8 the slide bar 40^a has a guide pin 41^a at its upper end fitting in a recess 42^a and is cushioned by a coil spring 43^a seated in the recess 42^a. The slide 40^a is actuated by the head 45^a of an actuating lever and has a lock operating projection 51^a. Mounted upon a pivot 52^a centrally of the casing is a lever 53^a having a depending pivoted actuating arm 54^a which may carry a bearing roller 55^a and has an inwardly projecting foot 56^a engageable with the underside of the head 45^a of the actuating lever. A link 58^a is pivotally connected to the opposite end of the lever 53^a and has a recess 59^a which receives a stud 60^a which is carried by the slide 40^a. The link 58^a has a spring receiving recess 61^a in its lower end portion in which is seated a coil spring 62^a, the upper end of which fits over a projection 63^a which may be provided on the underside of the stud 60^a and bears against the underside of the stud 60^a. Above the recess 59^a the link 58^a has a lug 65^a which projects laterally over the head 45^a of the operating lever. The spring 62^a normally holds the lug 65^a in engagement with the upper face of the head 45^a of the operating lever and the foot 56^a of the arm 54^a in engagement with the underside of the head 45^a, the operating lever being held in an intermediate position as in the modification shown in Figs. 6 and 7.

When the operating lever is moved in the direction to raise the head 45^a, the link 58^a is lifted and the slide 40^a is actuated through the spring 62^a. When the operating lever is moved in a direction to depress the head 45^a, the actuating arm 54^a is depressed swinging the lever 53^a about its pivot and lifting the link 58^a which causes the slide 40^a to be actuated by the link 58^a through the spring 62^a. In this modification the one spring 62^a serves to cushion the slide bar upon movement of the actuating lever in either direction.

In the modification shown in Fig. 9 the slides 67 and 68 are mounted in the upper and lower ends of the casing and carry upper and lower door bolts 69 and 70. A coil spring 71 is interposed between the ends of the slides 67 and 68 and serves to normally hold the door bolts in engaging position.

A lever 72 is pivoted at 73 to a central part of the casing. One end of the lever 72 has a link 74 connected to a lug 75 carried by the slide 67. The other end of the lever 72 has a link 76 connected to a lug 77 carried by the slide 68.

The mechanism so far described is substantially that shown in Figs. 6 and 7 of my Patent 1,288,816 granted Dec. 24, 1918. The operating lever has a head 78 projecting into a slot in the slide 68. Beneath the head 78 the slide 68 is slotted to receive a slide block 79 which is normally held against the head 78 of the operating lever by means of a coil spring 80.

As in the modifications above described, the operating lever is mounted to move toward the door to release the lock. It might happen that in an emergency the person first to the door would insist upon trying to pull the door inwardly by means of the lock actuating lever. The force thus exerted would act to force the bolts into their sockets at the top and bottom of the door. If sufficient force were exerted upon the actuating lever, this might cause the bolts to bind. With the spring cushion slide block as shown in Fig. 9, however, direct thrust upon the door bolts is prevented and as soon as the outward pull on the lever is released, the lever is returned to normal position, ready to be actuated in the proper direction to release the bolts.

In the modification shown in Fig. 10 the slide 81 carries a bolt 82 engageable at the top of the door. The actuating lever 83 in this case swings toward the door above its pivot to release the bolt. The lever 83 is pivoted to bosses 84 carried by the casing and has a head 85 projecting into a slot in the slide 81. Slidably mounted in the slide 81 above the head 85 is a block 86 which is held in engagement with the head 85 by means of a coil spring 87. The outward movement of the lever 83 is cushioned by the spring 87 which prevents the bolt 82 from being jammed into its socket by means of the lever 83. The spring 87 also serves to return the lever 83 to normal position when released.

Having described my invention, I claim:

1. In a device of the character described, the combination with a door having a lock, of a lock actuating mechanism, comprising a movable lock actuating member, an actuating lever for said lock actuating member, and a spring interposed between said actuating lever and lock actuating member.

2. In a device of the character described, the combination with a door having a lock, of a lock actuating mechanism, comprising a vertically movable slide bar carrying a lock operating member, an actuating lever for said slide bar and a spring interposed between said actuating lever and slide bar.

3. In a device of the character described, the combination with a door having a lock, of a lock actuating mechanism, comprising a vertically movable slide bar, having a lock operating projection, a spring resisting movement of said bar in one direction, an

actuating lever for moving said slide bar in opposition to said spring, and a spring interposed between said actuating lever and slide bar.

5 4. In a device of the character described, a combination with a door having a lock, of a lock actuating mechanism, comprising a vertically movable slide bar having a lock operating projection engageable with the door lock, a spring interposed between a part of said slide bar and the casing, a block slidably mounted in said slide bar, a spring interposed between the upper end of said block and the slide bar, and an actuating lever having a head engageable beneath said slide block and acting to press said block against its spring and to actuate said slide bar in opposition to its spring.

10 5. In a device of the character described, the combination with a door having a lock, of a lock actuating mechanism, comprising a movable member operable when shifted in one direction to release the door lock, an actuating lever, and yielding means interposed between said lever and movable member for shifting said member to release the lock upon actuation of said lever in either direction.

15 6. In a device of the character described, the combination with a door having a lock, of a lock actuating mechanism, comprising a slide bar carrying a lock actuating member and operable when shifted in one direction to release the door lock, an actuating lever, and connections between said lever and slide bar for shifting said bar in the direction to release said lock upon actuation of said lever in either direction, said connections including springs permitting movement of said lever independently of said slide bar.

20 7. In a lock operating mechanism, a casing having a pivot boss upon the outer face thereof, said boss having spaced outwardly projecting side portions, and an operating lever pivoted to said boss between the side portions thereof, the outer end of the lever adapted to be swung above or below the pivot, said lever having abutments above and below the pivot engageable with the casing, said boss projecting beyond said pivot and forming a guard for one of said abutments.

25 8. In a lock operating mechanism, a casing having a pivot boss upon the outer face thereof, said boss having spaced outwardly projecting side portions, and an operating lever pivoted to said boss and movable between the said outwardly projecting portions of the boss, said lever having a projecting portion engageable with said boss to limit its movement in one direction and an abutment lying between the side portions of the boss and engageable with the casing to limit its movement in the opposite direc-

tion, said boss extending beyond the pivot to form a guard for said last mentioned abutment.

9. In a device of the character described, a casing adapted to be attached to a door, a lock operating lever pivoted to the casing, said lever having at its outer end an attaching portion adapted to receive a push bar, said attaching portion having a part projecting inwardly from the push bar and adapted to engage the casing to limit the inward movement of the lever.

10. In a device of the character described, the combination with a door having a lock, of a lock actuating mechanism, comprising a slide bar carrying a lock actuating member and operable when shifted in one direction to release the lock, a movably mounted spring pressed member carried by said slide bar, an actuating lever engaging said member and acting upon movement in one direction to shift said member in opposition to its spring and through said spring to actuate said slide bar in a direction to release said lock, and means for shifting said slide bar in the same direction upon movement of the actuating lever in the opposite direction, said means consisting of a lever pivoted intermediate its ends to the casing and having means at one end engageable with said actuating lever and a spring connection at its opposite end with said slide bar.

11. In a device of the character described, the combination with a door having a lock, of a lock actuating mechanism, comprising a movable lock actuating member, a lever pivoted to the casing, and a link pivoted to said lever and having a spring connection with said lock actuating member.

12. In a device of the character described, the combination with a door having a lock, of a lock actuating mechanism comprising a slide bar, an actuating lever for the slide bar and a spring interposed between said actuating lever and slide bar.

13. A lock operating device comprising a longitudinally movable slide, means acting on said slide tending to shift the same in one direction, an actuating member for moving the slide in opposition to said means, and a yielding cushion interposed between said actuating member and slide.

14. A lock operating device comprising a casing, a slide mounted for longitudinal movement in the casing, a spring interposed between the slide and casing, and a lever for actuating said slide in opposition to said spring, said lever being yieldably connected to the slide.

15. A lock operating device comprising a longitudinally movable slide, a longitudinally extending slot in said slide, a movable actuating member extending into said slot, and a compression spring mounted in said

slot and normally holding said actuating member at one end of the slot.

16. A lock operating device comprising a casing, a longitudinally movable slide mounted in the casing, a spring interposed between the casing and slide, a lever for actuating the slide in opposition to said spring, and a cushioning device interposed between the lever and slide comprising a second spring through which pressure is transmitted from the lever to the slide, said second spring being stronger than said first mentioned spring.

17. A lock operating device comprising a casing, a longitudinally movable slide in the casing, a spring interposed between the slide and casing, a yielding member associated with the slide, and a lever engageable with the yielding member and acting through said yielding member to shift the slide in opposition to the spring.

18. A lock operating device comprising a casing, a longitudinally movable slide mounted in the casing, a compression spring interposed between the slide and casing, a second compression spring movable with the slide, means for limiting the expansion of said second spring, and a lever acting through said second spring to move the slide in opposition to said first spring.

19. A lock operating device comprising a casing, a longitudinally movable slide mounted in the casing, a spring interposed between the slide and casing, a lever pivoted to the casing, a link connected to the lever and extending alongside the slide, said link having a projection engageable with the slide to limit the longitudinal movement of the link in one direction with respect to the slide, a spring interposed between the link and slide and acting to normally hold the projection on the link in engagement with the slide, and means for actuating the lever in a direction to actuate the link in a direction to actuate the slide through the interposed spring.

20. A panic bolt, having, in combination with a horizontally disposed push bar, attachment plates in which the ends of said push bar are pivotally mounted, a latch en-

gaging member slidably mounted in one of said attachment plates in position to be actuated by a projecting end of said push bar when the latter is pressed inwardly and downwardly, and plural means of unequal strength for yieldingly holding said latch-engaging member in non-actuating position.

21. In combination with a pair of face plate members adapted for attachment to a door adjacent opposite edges thereof, a latch-engaging member supported in that one of said face plate members adjacent the free or swinging edge of the door, a plurality of spring members for yieldingly holding said latch-engaging member in non-actuating position, said spring members being of variant strength whereby they act in succession rather than simultaneously, and a push bar pivotally supported by said face plate members in position for one of its ends to actuate said latch-engaging member when pushed toward the door.

22. The combination, with a supporting face plate, of a push bar terminal pivotally supported thereby in position to swing through a plane perpendicular to that of the face plate, a latch-actuating member slidably supported in operable relation thereto, and a pair of oppositely acting springs of unequal resiliency, through and regulated by which the lifting pressure of the push bar terminal on the latch-actuating member is resiliently communicated to the latch.

23. In combination with a latch member appurtenant to the free or swinging edge of a door, an emergency actuating member therefor, consisting of a supporting face plate, a latch-actuating member capable of limited sliding movement thereon, an impact-cushioning element comprising a pair of oppositely acting springs of different resiliency, and an actuating lever pivoted to said face plate in position to engage said impact-cushioning element when moved toward the door from its normal outwardly swung position.

In testimony whereof, I hereunto affix my signature.

WILLIAM B. BOLLES.
